INDOOR STORM CURTAIN

Willis O. Higby, Turin, N. Y.

Application August 26, 1937, Serial No. 161,129

6 Claims. (Cl. 20—40)

This invention relates to improved means for insulating wall openings in the nature of windows and pertains particularly to an improved curtain for forming such insulation means.

5 The present invention has for its primary object to provide an improved curtain structure of transparent material, and means for securing the same upon the inner side of a window, whereby a dead air space will be set up against the inner 10 side of the window glass so as to provide an effective insulation means for preventing the loss of heat through the window.

Another object of the invention is to provide a transparent curtain for the purpose above set 15 forth, in which a novel means is employed for securing the edges of the curtain to the window frame so as to effectively prevent the circulation of air between the curtain and window.

A still further object of the invention is to provide 20 an improved curtain formed of transparent cellulosic material in the nature of cellophane with novel means for securing the curtain while in use to prevent longitudinal and transverse wrinkling of the same.

25 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in elevation of a window showing the device embodying the present invention applied thereto.

40 Fig. 2 is a view upon an enlarged scale of spring holding means for the edge of the curtain.

Fig. 3 is a sectional view taken on the line 3—3 of Fig. 2.

Fig. 4 is a plan view of a modified form of curtain holding means.

Fig. 5 is a sectional view on the line 5—5 of Fig. 4.

Referring now more particularly to the drawing, the numeral 1 generally designates the frame 50 of a window in which are slidably mounted the usual glass carrying sashes 2.

The curtain structure embodying the present invention is designed to be mounted upon the top cross bar 3 of the frame above the usual 55 shade roller which is generally indicated by the

numerical 4. This inside storm curtain comprises a sheet of transparent material which is generally indicated by the numeral 5 and which consists of the transparent cellulosic substance, of which one form is marketed under the name 5 "Cellophane." This sheet of transparent material is formed of the proper width and length to completely cover the window frame, and one end edge of the same is secured to a roller 6 which has the same construction as the roller 10 commonly employed for carrying a shade, except for the fact that the usual pivoted dogs of the shade roller are removed so that the storm curtain roller can be turned freely, and for facilitating the rolling up of the transparent curtain 15 material thereon it has in the recess 7 which is formed in one end thereof, the usual spring 8 which is coupled with the rotatable trunnion 9. At the other end of the roller a fixed trunnion 10 is located, and these trunnions 9 and 10 are 20 mounted in the usual shade roll supporting brackets 11.

The transparent curtain carrying roller is mounted, as previously stated, upon the window frame above the usual shade roller 4, and the curtain 5 is drawn down between the frame and the shade roller, as illustrated. The end of the curtain 5 opposite from the roller 6 has secured thereacross a bar of iron 12, or any other suitable heavy material and the ends of this bar extend 25 beyond the side edges of the curtain 5 and are provided with the apertures 13 to receive the retaining pins 14 which are secured in the side portions 15 of the window frame at the lower ends thereof. By the provision of the bar 12 at the 30 lower edge of the transparent curtain and the pins 14 for connection with this bar when the curtain is drawn down, the curtain is securely held against the tension of the wound spring 8 so that it will be prevented from returning to its 35 rolled-up position and also it will be prevented from developing transverse wrinkles which might otherwise form in the material of which it is formed.

In order to maintain the side edges of the 45 curtain 5 close against the side portions 15 of the window frame, there is provided a series of springs for attachment along the length of the face of each side portion of the frame. Each of these springs comprises a loop of spring wire 50 16 which at one end has an eye 17 through which a securing screw 18 is passed. This screw not only fixes the inner end of each spring 16 relative to the adjacent edge of the transparent curtain, but also holds the spring in firmly against the 55

face of the frame so that when the free end of the spring is engaged with the edge of the curtain it will force this edge against the frame and thus set up a relatively tight joint between the 5 frame and curtain.

The free end of each spring wire 16 is provided with a hook 19 and formed along each longitudinal edge of the curtain 5 is a series of apertures 20 each of which is encircled by a suitable 10 annular reinforcement 21 which prevents the hook 19 of the spring from tearing the curtain material. The number of apertures 20 along each side of the curtain equals the number of springs attached to the adjacent side of the window 15 frame, and when the curtain is drawn down so that the bar 12 may be engaged with the retaining pins 14, each aperture 20 will be located adjacent to a spring 16 and the hooked end portion of the adjacent spring is then engaged in the 20 aperture. Since the natural tendency of each spring is to turn or curl in toward the screw 18 to which it is attached, it will be apparent that the spring must be placed under tension in order to move the hook 19 outwardly for engagement 25 in the adjacent curtain aperture 20 and thus when the spring is released it will tend to pull the curtain toward the screw to which it is attached, and since the springs upon the opposite side are pulling in the opposite direction, it will 30 be apparent that the curtain will be securely held so that the formation of longitudinal wrinkles therein will be prevented. At the same time the springs will act to firmly secure or retain the edges of the curtain against the face of the window frame so as to prevent the free passage of 35 air and thus the air trapped between the curtain and the window panes will remain stationary and form an effective insulation covering for the window to prevent loss of heat through the same.

40 Fig. 4 illustrates a modified form of the spring holding means for the edges of the storm curtain. In this form there is provided a disc 22 of heavy paper or pasteboard or some other suitable material which carries an adhesive upon one surface so as to facilitate its being secured by this medium to the side portion 15 of the window frame in place of the screw 18 used for attaching the spring 16. This disc 22 carries a central post 22 to which is attached one end of the spring wire 23, the outer end of which is provided with a hook 24 for use in the same manner described in connection with the spring 16. By providing these gummed or adhesive carrying discs the springs may be attached to the faces of the side 50 portions 15 of the window without marring the woodwork and thus if it is desired to remove the curtain this can be done without leaving any holes or other abrasions in the surface of the window.

60 When it is desired to raise the curtain 5, this may be easily accomplished by disengaging the terminal portions 19 or 24, as the case may be, of the hooks from the apertures 20, and then oscillating the spring body 16 or 23 in a clock-wise 65 direction around the members 18 or 24, respectively, by which they are attached to the frame. This will free the edges of the curtain and remove the hooks from the proximity thereof so that the curtain may be readily shifted in the desired 70 direction without danger of it becoming torn. It will be readily apparent that when the hooks are to be placed back in operation, the stated clock-wise rotation or oscillation thereof may be continued until they are brought back into the prop-

er positions over the curtain for engagement in their respective apertures.

As will be readily apparent from the foregoing, a novel feature of the present invention resides in the fact that a storm curtain can be easily 5 and quickly drawn into position across a window when necessary and while it is in use no light will be prevented from entering through the window. The device may also be economically constructed so that it may be sold at a reasonable 10 price and thus be made available where more expensive storm curtain structures could not be used.

I claim:

1. An indoor storm curtain for use over wall 15 openings such as windows and the like, comprising a roller adapted to be rotatably supported across the top of said opening, a sheet of transparent material secured along one edge to said roller, a weighted bar secured along the opposite 20 edge of said sheet of material, said sheet of material having reinforced apertures along its side edges, and a plurality of retaining elements for the said side edges of the curtain each comprising securing means for attachment to the side 25 of the opening and a resilient element carried by said means for movement in a plane parallel with the faces of the sheets and adapted to engage in one of said apertures in the sheet and constantly exerting a pull on and transversely 30 of the sheet while maintaining the adjacent edge thereof in contact with the adjacent wall.

2. An indoor storm curtain for use over wall 35 openings such as windows and the like, comprising a roller adapted to be rotatably supported across the top of said opening, a sheet of transparent material secured along one edge to said roller, a weighted bar secured along the opposite edge of said sheet of material, a plurality of 40 retaining units for the said side edges of the curtain each comprising securing means for attachment to the side of the opening and a resilient element carried by such means and formed to swing thereon in a plane parallel with the faces of the sheet having a hook-like terminus, and 45 means adjacent the edges of said sheet for engagement by the said terminus of an adjacent element whereby the resilient element will be under tension when engaging said last means and exert a pull on the sheet to maintain the same 50 taut.

3. An improved curtain of the character described for disposition over a window opening, comprising a supporting roller, a sheet of transparent material secured along one edge to said 55 roller, said sheet of material having a plurality of apertures formed therethrough along each side edge, means at the edge of the material remote from the roller for securing the same to the lower part of a window opening, and means for securing 60 the said apertured edges of the curtain to the sides of the window opening comprising a plurality of units each consisting of a body adapted to be secured to the side of the window and a resilient wire attached thereto and swingable on 65 the unit in a plane parallel with the faces of the sheet and having an end formed to engage in an aperture of the curtain and maintained under tension when so engaged to exert a pull on the curtain opposing the pull of the units at the opposite edge thereof.

4. An improved curtain of the character described for disposition over a window opening, comprising a supporting roller, a sheet of transparent material secured along one edge to said 75

roller, said sheet of material having a plurality of apertures formed therethrough along each side edge, means at the edge of the material remote from the roller for securing the same to the lower 5 part of a window opening, and means for securing the said apertured side edges of the curtain to the sides of the window opening comprising a plurality of units each consisting of a securing screw for engagement in the side of the window 10 opening and a flat wire spring having one end attached to said screw and adapted to be swung thereon in a plane paralleling the faces of the sheet and secured to the window by the screw and having its other end in the form of a hook 15 adapted for engagement in an adjacent aperture in the curtain and maintained under tension by such engagement.

5. An improved curtain of the character described for disposition over a window opening, 20 comprising a supporting roller, a sheet of transparent material secured along one edge to said roller, said sheet of material having a plurality of apertures formed therethrough along each side edge, means at the edge of the material remote 25 from the roller for securing the same to the lower part of a window opening, and means for secur-

ing the said apertured side edges of the curtain to the sides of the window opening comprising a plurality of units each consisting of an adhesive carrying disc adapted to be secured to the face of the frame of the window opening, a pin carried by the disk, and a flat wire spring secured at one end to the pin and having its other end formed in a hook for engagement in an adjacent aperture in the curtain and maintained under tension by such engagement. 10

6. An indoor roll-up storm curtain for use over wall openings such as windows or the like, comprising a sheet of transparent material adapted to cover said opening, means at the top of the window for supporting said sheet whereby the 15 same may be rolled up, means at the bottom of the sheet for maintaining the same longitudinally taut when unrolled, a plurality of units secured to the wall structure at each side edge of the sheet, each including an element adapted to engage the curtain and exert a transverse pull thereon in opposition to the opposite units and simultaneously press the adjacent edge of the curtain against the wall structure. 20
